(57) **CLAIM**

The ornamental design for an adjustable headstock for a bicycle, as shown and described.

DESCRIPTION

FIG. 1 is an upper perspective view of the adjustable headstock for a bicycle showing my design.

FIG. 2 is a side elevation view thereof;

FIG. 3 is a front elevation view thereof;

FIG. 4 is an opposite side elevation view thereof;

FIG. 5 is a top plan view thereof;

FIG. 6 is a bottom plan view thereof;

FIG. 7 is a back elevation view thereof; and,

FIG. 8 is a side elevation view thereof, showing attachment to a bicycle.

The broken line features in FIGS. 1-8 are environment and form no part of the claimed design.
